DESIGN FOR A SPLICING SLEEVE COM- PRESSING TOOL

Frank J. Mayer, Cleveland, Ohio, assignor to The
National Telephone Supply Company, Cleve-
land, Ohio, a corporation of Ohio

Application May 5, 1939, Serial No. 84,819

Term of patent 14 years

To all whom it may concern:

Be it known that I, Frank J. Mayer, a citizen
of the United States and a resident of Cleveland,
county of Cuyahoga, and State of Ohio, have in-
vented a new, original, and ornamental Design
for a Splicing Sleeve Compressing Tool, of which
the following is a specification, reference being
had to the accompanying drawing, forming a
part thereof.

In said annexed drawing:

Fig. 1 is a plan view of the splicing sleeve com-
pressing tool, showing my design;

Fig. 2 is a cross-sectional view, taken on the
line 2—2 of Fig. 1;

Fig. 3 is a cross-sectional view, taken on the line
3—3 of Fig. 1;

Fig. 4 is a cross-sectional view, taken on the
line 4—4 of Fig. 1, and

Fig. 5 is a side view of the tool, as viewed from
the left side of Fig. 1.

I claim:

The ornamental design for a splicing sleeve
compressing tool, as shown.

FRANK J. MAYER.
